CLAIM

The ornamental design for an combined holder and visual stimulator for infants, as shown and described.

DESCRIPTION

FIG. 1 is a perspective view of a combined holder and visual stimulator for infants embodying the design of the present invention;

FIG. 2 is a front elevational view thereof;

FIG. 3 is a top plan view thereof;

FIG. 4 is a bottom plan view thereof;

FIG. 5 is a side elevational view thereof, the undisclosed side being a mirror image; and

FIG. 6 is a rear elevational view thereof.

Fig.1.**Fig. 2.****Fig. 3.****Fig. 4.****Fig. 5.****Fig. 6.**
